UNITED STATES PATENT OFFICE.

FRANK ELMER WELKER, OF BEAVER CREEK, MINNESOTA.

SPARK-PLUG.

1,249,573.

Specification of Letters Patent. Patented Dec. 11, 1917.

Application filed January 17, 1917. Serial No. 142,840.

To all whom it may concern:

Be it known that I, FRANK E. WELKER, a citizen of the United States, and a resident of Beaver Creek, in the county of Rock and State of Minnesota, have invented certain new and useful Improvements in Spark-Plugs, of which the following is a specification.

My invention is an improvement in spark plugs, and has for its object to provide a plug of the character specified, wherein the electrodes are so arranged and placed that they will be free from grease, soot and sediment, while at the same time they will furnish a spark of the character required to provide good ignition.

In the drawing is shown a sectional view of the improved plug.

In the present embodiment of the invention a shell 1 is provided of metal, externally threaded at its one end for engaging the cylinder, and this shell is internally threaded to receive a plug 2 of porcelain or other insulating material, the said plug entirely filling the cavity of the shell and held by the threads.

Within the material of this plug is arranged one of the electrodes 3, the said electrode being grounded to the shell and to the engine. The plug 2 is of sufficient length to extend beyond the lower end of the shell as shown, and this end is rounded and transversely notched or recessed to form a spark chamber 4. The other electrode 5 is also embedded in the material of the plug 2, and the lower ends of the said electrodes are curved as shown, into the chamber 4, and they are spaced apart to form the spark tap.

At the upper end of the shell a tapered opening 6 is provided, and within this opening is arranged a tapering or conical insulating sleeve 7 of mica or the like, the said sleeve closely encircling the electrode 5. Within the plug the electrode 5 is offset laterally away from the center, but at the sleeve 7 the electrode is at the center. The upper or small end of the sleeve 7 extends through the opening 6 and above the shell as shown. A tapering sleeve 8 of porcelain

or the like, is arranged on the shell, the large end of the sleeve being spaced from the shell by a washer 9, and the bore of the sleeve 8 is greater than the exterior diameter of the sleeve 7 in order that there will be an annular chamber 10 between the sleeves 7 and 8.

A washer 11 is arranged at the small end of the sleeve, and a nut 12 is threaded onto the electrode where it extends beyond the washer 11. The spark plug is completed by a cap 13 which is threaded upon the extended end of the electrode above the nut 12. With the improved spark plug, the points of the electrode are protected from grease, soot and sediment, being within the chamber 4, while at the same time an efficient spark is provided insuring good ignition. The nut 12 and the cap 13 are of conducting material to permit the connection of the lead wire 70 with the electrode.

I claim:

1. A spark plug comprising a metal shell, a plug of porcelain within the shell and extending below the same, the extended end 75 being rounded and having a transverse notch or recess, electrodes embedded within the plug and extending into the notch or recess at one end, one of the electrodes engaging the shell and the other being insulated therefrom, said last named electrode extending above the shell, an insulating sleeve between the electrode and the shell at the said extended end, a protecting sleeve encircling the last named sleeve in spaced relation and 80 engaging the upper end of the shell, a nut threaded onto the electrode above the last named shell, and a cap threaded onto the electrode above the nut.

2. A spark plug comprising a metal shell, 90 an insulating plug within the shell and extending below the same, the extended end having a transverse notch or recess, and electrodes embedded within the plug and extending into the recess, said electrodes being 95 spaced apart from the bottom of the notch.

FRANK ELMER WELKER.
